UNITED STATES PATENT OFFICE.

LADISLEAS LENGYEL, OF CLYMER, PENNSYLVANIA.

BREAST DRILL.

Application filed January 31, 1924. Serial No. 689,794.

To all whom it may concern:

Be it known that I, LADISLEAS LENGYEL, a citizen of Hungary, residing at Clymer, in the county of Indiana and State of Pennsylvania, have invented certain new and useful Improvements in Breast Drills, of which the following is a specification.

This invention relates to certain new and useful improvements in breast drills and has for its primary object to provide a cushioned or resiliently supported shaft to which the drill is attached for holding the drill in resilient engagement with the work being operated upon and reducing the transmission of vibration between the drill and the body of a person engaging the same.

With the above and other objects in view that will become apparent as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a side elevational view of a breast drill constructed in accordance with the present invention, the drill bit and the operating means therefor being illustrated by dotted lines,

Figure 2 is an end elevational view of the breast frame of the drill,

Figure 3 is an enlarged fragmentary sectional view showing the resilient mounting for the rod to which the drill bit is attached,

Figure 4 is a cross-sectional view taken on line IV—IV of Fig. 1,

Figure 5 is an enlarged fragmentary detail sectional view showing the end thrust ball bearing for the drill bit supporting rod,

Figure 6 is a plan view of the connected plate members supporting the bearing ball, and

Figure 7 is a plan view of one of the retainer plates for the bearing ball.

Referring more in detail to the accompanying drawing, there is illustrated a breast drill including a breast frame of U-shape formation having a cross plate 1 and angularly bent end arms 2 to which a U-shaped frame plate is attached, the frame plate including a cross plate 3 and angu-

larly bent end arms 4 having their free ends secured as at 5 to the breast plate 1 as clearly shown in Fig. 1.

A socket member 6 is resiliently supported upon the breast and frame plates 1 and 3 respectively, the socket member 6 freely projecting through an opening 7 centrally formed in the frame plate 3, the socket member carrying an enlarged head 8 upon the inner end of which there is provided with an opening affording an unrestricted passage through the socket member and head with the latter disposed inwardly of the frame plate 3 for limiting outward movement thereof. Diametrically opposite arms 9 are carried by the head 8 and are provided adjacent the outer ends thereof with openings 10 through which rods 11 freely extend. The headed ends 12 of the rods 11 are anchored to the breast plate 1 while the forward ends thereof are threaded as at 13 and freely extend through openings 14 in the frame plate 3 to have securing nuts 15 mounted thereon to retain the bolts 11 in position. A coil spring 16 surrounds each bolt 11 between the breast plate 1 and the arms 9 of the socket member 6 for resiliently supporting the socket member and retaining the same tensioned in an outward direction.

The inner end of the socket member 6 and head 8 carried thereby has an end thrust bearing ball disposed therein, a pair of ball retainer plates 17 in the form of disk members having central openings surrounded by concaved ball engaging feet 18 and provided with opening 19 permitting the retainer plates being retained in assembled position by the screw members 20 encloses opposite sides of a bearing ball 21 as clearly shown in Fig. 5. The bearing ball and retainer plates are inserted in the headed end of the socket member 6, the outer plate 17 engaging the shoulder 22 formed upon the inner wall of the socket member while a screw plug 23 threaded into the head 8 as at 24 carries a block 25 having a concave seat 26 in its outer side that receives the bearing ball 21.

A drill bit supporting rod 27 is freely mounted in the socket member 6 as shown in Figs. 3 and 5 and engages at its inner end the end thrust bearing ball 21. As shown by dotted lines in Fig. 1, a sleeve

28 has a swivel connection 29 with the rod 27, the rod projecting outwardly of the sleeve 28 and having a drill bit 30 detachably connected thereto in any suitable manner. A bracket arm 31 carried by the sleeve 28 rotatably supports a shaft journaled in the bearing 32, the outer end of the shaft having a crank handle 33 secured thereto while the inner end of the shaft in the bearing 32 extends beyond the angle bracket 31 and carries a bevel gear 34 that meshes with the bevel gear 35 keyed to the rod 27. A gripping handle 36 projects from the sleeve 28 diametrically opposite the angle bracket 31 so that the handle 36 may be gripped by one hand while the other hand of the operator is employed for operating the crank circuit 3.

In the use of the drill, the body of the 20 person using the same is moved with pressure against the breast plate 1 and the drill foot 30 is forced into engagement with the work, the engagement between the drill bit and the work being cushioned by the 25 coil springs 16 that are compressed by the rod 27 rotating in the socket member 6 and engaging the hand thrust bearing ball 21 to move the socket member and lateral arms 9 carried thereby inwardly toward the 30 breast plate 1 to compress the coil springs 16. It will therefore be seen that during the entire use of the drill, the drill supporting rod 27 is resiliently supported and that shocks and vibration incident to the 35 use thereof or partially removed from the breast plate 1 and absorbed by the spring devices 16 and the resiliently supported socket member 6.

While there is herein shown and described 40 the preferred embodiment of the present invention, it is nevertheless to be understood that minor changes may be made

therein without departing from the spirit and scope of the invention as claimed.

What is claimed as new is:—

1. In a breast drill of the type described, a breast plate, a frame plate secured to the breast plate, a drill supporting socket member resiliently mounted upon the frame and breast plate, a manually operable drill supported in the socket member, the resilient mounting for the socket member including spring devices interposed between the frame and breast plate and constituting a support for the socket member. 45

2. In a breast drill of the type described, a breast plate, a frame plate secured to the breast plate, a drill supporting socket member resiliently mounted upon the frame and breast plate, a manually operable drill 50 supported in the socket member, the resilient mounting for the socket member including a pair of rods extending between the breast and frame plate, coil springs surrounding the rods and lateral arms carried by the 55 socket member freely slidable upon said rods and engaging the outer ends of said springs. 60

3. In a device of the kind described, a breast plate consisting of a substantially 70 U-shaped bar, a frame plate consisting of a U-shaped bar having its legs secured to the breast plate and provided with a centrally disposed opening brace rods connecting said plates at opposite sides of said opening, a 75 socket carrier having arms slidable on said rods, springs surrounding the rods between the socket carrier and breast plate, and a socket supported by said carrier and reciprocable through the opening in the frame 80 plate. 85

In testimony whereof I affix my signature.

LADISLEAS LENGYEL.
